CLAIM

The ornamental design for a display screen with stand, as shown and described.

DESCRIPTION

Display screen with stand

Fig. 1.1 is a perspective view of our new design for a display screen with stand.

Fig. 1.2 is a perspective view of the display screen with stand of Fig. 1.1 with the arm and display in a different position, all other surfaces being the same.

Fig. 1.3 is a front side elevation view of Fig. 1.1

Fig. 1.4 is a back side elevation view of Fig. 1.1

Fig. 1.5 is a top plan view of Fig. 1.1

Fig. 1.6 is a bottom plan view of Fig. 1.1

Fig. 1.7 is a right side elevation view of Fig. 1.1

Fig. 1.8 is a left side elevation view of Fig. 1.1

Fig. 1.9 is a perspective view of the display screen with stand of Fig. 1.1 with the arm and display in a different position, all other surfaces being the same.

The broken lines showing portions of the display screen with stand are included for the purpose of illustrating portions of the article and form no part of the claimed design.
